UNITED STATES PATENT OFFICE.

PAUL GERVAIS, OF SEEBURG, GERMANY.

DIRECT-ACTING GAS-ENGINE.

SPECIFICATION forming part of Letters Patent No. 736,715, dated August 18, 1903.

Application filed January 2, 1902. Serial No. 88,078. (No model.)

To all whom it may concern:

Be it known that I, PAUL GERVAIS, a subject of the King of Prussia, Emperor of Germany, residing at Seeburg, in the Kingdom 5 of Prussia, Germany, have invented Improvements in Direct-Acting Gas-Engines, of which the following is a specification.

This invention relates to improvements in gas-engines of the rotary class in which the 10 motive parts are impelled by a continuous supply of the actuating fluid or products of combustion.

The object of the invention is to provide a device of such construction that will accomplish a constant and even actuation of the 15 turbine.

To this end the invention consists of a gas-engine comprising twin explosion-cylinders, gas-supply pipes therefor, means for alternating the supply of gas to the cylinders, 20 double receiving-chambers, separate communicating means between said cylinders and chambers, means for directing the product of combustion alternately in said communicating 25 means, and a turbine to be actuated by the product of combustion, as will be more fully described hereinafter and finally pointed out in the claim.

In the accompanying drawings, Figure 1 is 30 a vertical longitudinal section of the engine on line A A, Fig. 4. Figs. 2 and 3 are respectively plan and side views of the device; and Fig. 4 is a vertical transverse section on line B B, Fig. 3.

Similar letters of reference indicate corresponding parts.

Referring to the drawings, *a a'* represent the twin explosion-cylinders that are arranged parallel to each other, inclosed at one end by 40 the plate *b*, and each at the opposite end is provided with the shut-off valve *c*, that is maintained in closed position by its own weight. The oil-supply pipe *d* is divided to communicate with the cylinders through the 45 valves *e e'*. Communication from the ends *f* of the cylinders to the chamber *g* is had when the valves *c* are open. The receiving-chambers *h i* are cylindrical and arranged concentrically, the latter within the former. The 50 receiving-chamber *h* communicates with the chamber *g*, while the receiving-chamber *i*

communicates with the explosion-cylinders *a a'* through the pipe *q* and the valves *p p'* at the upper end of the pipe *q*, that branches laterally. Through the center of the receiving-chambers is arranged the power-shaft *k*, upon which at one end in the exhaust-chamber the turbine *l* is mounted and at the opposite end the pulley *x*, and around the shaft *k*, within the cylinder *i*, is arranged the inner 55 closing tube *z*. The receiving-chambers are separated from the exhaust-chamber *n* by the partition *m*. The partition-wall *m* is provided with the diametrical openings *r*, through which the products of combustion escape from 60 the chamber *i* to act upon the turbine *l*, while through the openings *r'* the products of combustion escape from the receiving-chamber *h* to act upon the turbine, and after acting 65 upon the turbine they escape from the exhaust-chamber *n* through the exhaust-pipe *o*.

The explosions of the gas in the twin cylinders take place alternately, and for this reason the valves *e* and *e'* are actuated alternately. To accomplish this, a cam mechanism is provided at one side of the device, a separate cam for actuating each valve *e e' p p'*. These cams *s s' s'' s'''* are mounted upon the shaft *v*, that is actuated by means of the gear-wheels *w* of the train of gears that is 75 actuated from the power-shaft *k*. Upon the cams rest the levers *t*, that are connected with the valves by the rods *u*. In the operation of the device the combustible gas or fluid is supplied to one of the combustion-chambers, preferably *a* for the purpose of 80 illustration, through the pipe *d* when the valve *e* is actuated by the cam *s'''*. When a sufficient quantity of combustible fluid or gas has entered the combustion-chamber *a*, 85 ignition takes place by means of the igniter *y*. Upon explosion the valve *c* is forced open and the expanding gas enters the receiving-chamber *h* through the chamber *g*; but before the products of combustion are 90 entirely exhausted from the explosion-chamber *a* a combustible gas or fluid is fed to the combustion-chamber *a'* by the actuation of its valve and explosion takes place, the expansive force of which acts upon the valve *c* 95 of the explosion-chamber *a* and closes the same. Upon the second explosion and the 100 same.

closing of the valve *c* of the chamber *a* the product of combustion confined in said cylinder escapes through the valve *p*, actuated by the cam *s'*, to be conveyed through the pipe 5 *q* to the receiving-chamber *i*. In this manner by the alternate explosions in the explosion-chambers *a* *a'* the products of combustion are conveyed to the receiving-chambers *h* *i* by the alternate closing and opening of the 10 valve *c* and valves *p* *p'*. By this construction the products of combustion are conveyed directly through the chambers *g* and *h* to act upon the turbine *l* and indirectly from the explosion-cylinders through the tube *q* and 15 the chamber *i* to act upon the turbine *l*, after which the products of combustion pass through the exhaust-chamber *n* and out of the exhaust-pipe *o*. The explosions are adapted to take place at frequent intervals 20 and by the direct and indirect play of the products of combustion upon the turbine causes a continuous and rapid actuation thereof, so that high speed and power is attainable.

25 Having thus described my invention, I

claim as new and desire to secure by Letters Patent—

In a rotary gas-engine, the combination of twin explosion-cylinders, a shut-off valve provided for each cylinder, separate receiving-chambers, separate means communicating from said cylinders to said receiving-chambers, spring-actuated valves for controlling the supply of gas to said cylinders, spring-actuated valves for permitting the escape of 30 a portion of the products of combustion to one of said receiving-chambers, a cam mechanism for actuating alternately said spring-actuated valves, said shut-off valves being opened and closed alternately by the explosion of the gas, a turbine, means for directing continuous supply of the products of combustion upon said turbine, and an exhaust, substantially as set forth.

In witness whereof I have hereunto set my 45 hand in presence of two witnesses.

PAUL GERVAIS.
